(57) CLAIM

The ornamental design for a headwrap with visor, as shown and described.

DESCRIPTION

FIG. 1 is a top plan view of a headwrap with visor showing my new design from the top in an untied condition;

FIG. 2 is a bottom plan view thereof, shown in the untied condition;

FIG. 3 is a side elevation view thereof, shown in a tied condition on the head of a wearer, the opposite side being a mirror image thereof;

FIG. 4 is rear elevation view thereof in the tied condition; and,

FIG. 5 is top plan view thereof in the tied condition.
